CHAIR CASTER

David R. Appel, Grand Rapids, Mich., assignor to Steelcase, Inc., Grand Rapids, Mich., a corporation of Michigan

Filed Mar. 18, 1968, Ser. No. 11,007

Term of patent 14 years

(Cl. D10—6)

FIG.1

FIG.2

FIG.3

FIG.4

FIG.5

FIG. 6

FIG. 8

FIG. 10

FIG. 7

FIG. 9

FIG. 1 is a perspective view of a chair caster which represents a first embodiment of the design of my invention;

FIG. 2 is a front elevational view of the caster shown in FIG. 1;

FIG. 3 is a side elevational view of the caster shown in FIGS. 1 and 2, the opposite side being identical;

FIG. 4 is a rear elevational view of the caster shown in FIGS. 1, 2, and 3;

FIG. 5 is a plan view of the caster of FIGS. 1 through 4;

FIG. 6 is a perspective view of a caster which represents a second embodiment of the design of my invention;

FIG. 7 is a front elevational view of the caster shown in FIG. 6;

FIG. 8 is a side elevational view of the caster shown in FIGS. 6 and 7, the opposite side being identical;

FIG. 9 is a rear elevational view of the caster shown in FIGS. 6, 7, and 8; and

FIG. 10 is a plan view of the caster of FIGS. 6 through 9.

I claim:

The ornamental design for a chair caster, substantially as shown and described.
